MASSAGE TABLE WITH ROLLERS

This invention relates to therapeutic devices and more particularly to a spinal massaging table arrangement where the pattern of travel of massaging rollers can be readily adjusted to conform to any particular spinal contour.

A more specific object of the invention is to provide, in a device of the type described, a track having a pair of rails for guiding the path of travel of massaging roller means mounted to a frame so that the elevation of various sections of the rails can be readily adjusted to provide a predetermined path of travel.

These and other objects of the invention will be apparent from an examination of the following description and drawings, wherein:

FIGURE 1 is a perspective view of a massaging device embodying features of the invention;

FIGURE 2 is a transverse vertical section taken on line 2-2 of **FIGURE 1**, with portions of the drawing being schematic;

FIGURE 3 is a plan view of a portion of the device of **FIGURE 1**, with portions of the structure broken away;

FIGURE 4 is a longitudinal vertical section taken on line 4-4 of **FIGURE 3**;

FIGURE 5 is a transverse vertical section taken on line 5-5 of **FIGURE 4**;

FIGURE 6 is a transverse section taken on line 6-6 of **FIGURE 5**; and

FIGURE 7 is a transverse vertical section taken on line 7-7 of **FIGURE 6**.

It will be understood that, for purposes of clarification, certain elements have been omitted from certain views where they are illustrated to better advantage in other views.

Referring now to the drawings for a better understanding of the invention, and particularly to **FIGURES 1** and **4**, it will be seen that the massaging device shown includes a horizontally disposed, generally flat plate or table **10** which may be covered with a resilient pad or cushion **12**, preferably formed of foam rubber. Both the table and cushion are provided with aligned, elongated openings **13** and **13a**, respectively, for receiving the massaging rollers in a manner hereinafter described.

Table **10** may be mounted over supporting structure which includes inner longitudinal and transverse braces or struts **16** and outer side and end members **18** carried on legs **19**.

As desired the device may be in the form of a conventional table or in the form of a bed, as illustrated. If the device is in the form of a bed, it, can serve a dual purpose. A cushion insert, not shown, may be placed in aligned openings **13** and **13a** to provide a smooth upper surface when the massaging apparatus is not being used.

Mounted on the table supporting structure under table **10** is a frame **20** for carrying the operating mechanism **24** of the device.

Frame **20** may be mounted, as by bolts **22**, to the cross braces **16** of the supporting structure.

Massaging mechanism **24** includes a pair of transversely extending front and rear sprocket shafts **26** mounted in the frame and carrying a pair of front and rear main sprockets **28** around which extends an endless conveyor chain **30**. It will be understood, of course, that pulleys and belts may be substituted for the sprockets and chain if desired.

Also mounted on rear sprocket shaft **26** is a driving sprocket **34** which is operatively connected by another chain **32** to a driving sprocket **36** mounted on the shaft **37** of a motor **38**.

Attached to conveyor chain **30** at spaced intervals by pins **41** are a plurality of yokes or clevises **40** each of which carry a roller shaft **42** on which is rotatably carried a cushioned massaging roller **44**.

As the rollers **44** and shafts **42** have to rotate freely in opposite directions, as hereinafter described, it will be understood that double sets of bearings are employed (not shown in detail) in mounting the rollers on the shafts and the shafts on the clevises.

The ends **46** of shafts **42** extend beyond the sides of the clevises and may be provided with auxiliary rollers **47** which

ride over a pair of rails **48** of a truck so as to serve as a guide means controlling the path of the massaging rollers as hereinafter described. It will be understood that the distance from the chain to the rail is less than the length of the clevises, so that rollers have freedom for limited vertical movement in following the contour of the rails. In order to prevent the rollers from flopping down when they leave the main rails at the trailing ends thereof, auxiliary return rails **49** may be provided and secured to the frame in a fixed position.

Now turning to **FIGURE 3** it will be seen that the rails have the general contour of a human spinal column so that the maximum therapeutic effect is achieved. It will be understood, of course, that the contours of all human spinal columns are not the same, and therefore a fixed position of the guide rails would not effect the desired result because pressure from the massaging rollers would not provide uniform pressure on spines of different contours if their path remains of the same contour at all times.

Herein resides the essence of this invention which is to provide a simple means of changing the elevations of different areas of the rails to thereby change the contour of the rails to provide a path of travel for the rollers of a particularly desired contour conforming to that of the spine of the person undergoing massage treatment.

In order to provide this adjusting means the rails are each secured to frame **20** by a plurality of longitudinally spaced, parallel, vertical supporting and adjusting rods **50**. Each of the rods **50** has its upper end **52** movably mounted in bracket **54** carried on the underside of a rail, as shown in **FIGURE 5**, and has a portion **56** adjacent its lower end threadably connected to a collar **58** which in turn is rotatably mounted in a horizontal portion of frame **20**, so that rotation of collar **58** will raise or lower that portion of the rail to which the upper end of the rod is connected.

Collar **58** is in the form of a wheel or spur having gear teeth **60** which engage teeth of a worm gear **62** carried on a transversely extending, horizontal control shaft **64** one end of which is mounted in a plate or bar **66** secured to a side member **18** of the supporting structure, as best seen in **FIGURES 4** and **7**.

At its outer end each bar **66** may be provided with a fitting **67** adapted to removably receive a crank handle **68**.

In operating the rail adjusting mechanism a previously made pattern of the spine of the user or patient may be placed alongside the rails while the crank is used to elevate or lower portions of the rails, which move in tandem with each other, as shown in **FIGURE 7**, to make the rail contour conform to the pattern.

After the rails have been adjusted the patient can lie on the table with his spinal column located over openings **13** and **13a** and receive a therapeutic massage wherein the pressure applied by the massaging rollers is uniform throughout the entire length of his spine because the path of travel of the rollers conforms to the contour of his spinal column. Of course the rollers may be changed, as desired, to provide the desired degree of hardness or softness of the pressure of the massage treatment.

Also, conventional means may be provided to control the speed of the conveyor chain and the duration of time. A control mechanism **70** may be conveniently mounted on a side member **18** of the supporting structure.

I claim:

1. A spinal massaging device, comprising, in combination:
  - (a) a table having an opening therein for receiving massaging roller means;
  - (b) a frame mounted under said table;
  - (c) massaging roller means carried by said frame, including:
    - (i) a plurality of roller elements attached at spaced intervals to an endless conveyor;
    - (ii) means for moving said roller elements linearly along the length of said opening;
    - (d) means for guiding the travel of said roller elements

along a path of a predetermined vertical contour which includes at least one rail mounted on said frame and engageable with said roller elements;
 (e) means for mounting said rail so that the elevations of spaced sections of the rail can be readily changed to control the vertical contour of the rail so that the path of travel of said roller elements conforms to a specific spinal contour.

2. A device according to Claim 1, wherein said mounting means includes a plurality of vertical rods having upper portions connected to the rail and having lower portions mounted in said frame for vertical movement relative thereto.

3. A device according to Claim 2, wherein said rod lower portions are each threadably received within a collar which is rotatably mounted in the frame and which has external gear teeth engageable with a worm gear carried by a horizontally disposed crankshaft.

4. A device according to Claim 1, wherein said guide means includes a pair of parallel rails the contour of which can be readily adjusted at the same time.

5. A device according to Claim 1, wherein said roller elements each includes:

- (i) a shaft;
- (ii) a cushion roller rotatably mounted centrally on said shaft for massaging a patient on said table;
- (iii) a pair of guide rollers rotatably mounted at opposite ends of said shaft for engagement with said guide means.

6. A device according to Claim 1, wherein said guide means includes a track for said roller elements, and said guide means includes means for raising and lowering spaced portions of said track to change its contour.
